ELECTRIC MATCH

Rene Gaston Richard, Springfield, Ill.

Application April 27, 1937, Serial No. 139,329

2 Claims. (Cl. 175—296)

The invention consists of a match or torch with a carbon tip, and electric terminal plates for igniting the match by means of an electric spark; and a safety provision for guarding the plates from the torch. One of the terminals is in the form of a grill, with alternate transverse bars and openings which serve as spark gaps; the other terminal consists of two upright plates fixed on both sides of the grill and parallel to it, with space between the upright plates to allow the match to be readily "struck" or drawn between them over the bars of the grill, being at the same time in contact with one of the plates; by which motion the current is alternately closed and broken, producing the necessary spark. The carbon tip of the match is kept moistened with an inflammable liquid.

Fig. 1 is a front view of my invention.
 Fig. 2 is an end view of my invention.
 Fig. 3 is a section taken on line 3—3 of Fig. 4.
 Fig. 4 is a section taken on line 4—4 of Fig. 3.
 Fig. 5 is a section taken on line 5—5 on Fig. 3.
 Fig. 6 is a plan view of the torch partly in section.
 Fig. 7 is a plan view of one of the contacts.
 Fig. 1 illustrates the complete front view ensemble of one form of the invention. The exterior form may be varied infinitely in its style. The sparking plates 5, 6—6 can as well be placed horizontally as vertically on the case, and instead of being raised above the surface, can be counter-sunk in a slot and made flush with the surface. No. 5 is the grill, held in place by two bolts 7—7, set between the guide plates 6—6. These plates are guarded by shields 13—13 of the same material as the exterior of the case, a non-conducting material. If the case be made of metal, the plates 6—6 will be insulated from the shields 13—13 by insulating material.
 Fig. 3 is an inside view of the invention in longitudinal vertical cross-section. No. 1 represents the match. No. 2 is a sleeve or tube to hold the match 1, thrust into a container 3 containing felt 4 soaked with inflammable fluid. This container 3 and sleeve 2 can be of any non-porous, durable substance.

Fig. 3 also illustrates the electric circuit. No. 10 is an ordinary plug to connect with the source of power, a 110- or 120-volt D. C. or A. C. current. From plug 10 the current passes through the wire P to an ordinary resistance coil or commercial transformer, and from thence by the wire S to the binding posts 8—8 on the upright plates 6—6. From the binding post 7 on the grill 5, Fig. 1, the

current is conducted by wire P2 back to the plug 10.

The invention is also adaptable to automobiles, in which case it can be operated from the battery current. In this adaption the resistance coil is 5 reduced or omitted, as the current from the ordinary 6- or 12-volt battery is of proper strength with little or no resistance.

Fig. 4 shows the position in side elevation vertical cross-section, illustrating the binding posts 10 8—8 holding the guide plates 6 rigidly in position against the face of the container. These plates 6 in turn are protected by the guards 13.

Fig. 5, a horizontal cross-section from above, illustrates the placing of the interior parts and 15 connections; also the safety principle, whereby the contact plates 5 and 6—6 are guarded from the touch of persons handling the apparatus by the shields 13—13, which are of insulating material, or insulated as described in the paragraph 20 relating to Figure 1. The edges of the plates 6—6 with their guarding shields 13—13 will be close enough together to prevent the insertion of a person's finger, and the shields 13—13 sufficiently prolonged to guard the open ends as well. The overhanging edges of the upright plates 6—6 are at the same time far enough apart to allow the match to pass freely between them with about 1/16 inch clearance or play.

Fig. 6 is the match, showing the three pieces 30 of which it consists. The handle 1A is made of a porcelain, Bakelite or a similar non-conducting substance. The tip 12 is made of hard, porous carbon, and is joined to the handle 1A with the sleeve of copper or other metal 11, fitting tightly 35 enough to hold the entire match rigidly together. The size of the match is a matter of no consequence, and may be varied to suit convenience or conform to the style of the container, subject to the considerations mentioned in the foregoing 40 paragraph.

Fig. 7 illustrates the metal grill 5 in detail. The openings between the bars break the circuit and produce the spark which ignites the match. 45 The grill is secured in place by the bolts 7—7, through the holes 7A—7A; one of which serves as a binding post for the wire P2 from the wall plug 10 as illustrated in Fig. 3. It is essential that the grill plate 5 should not be flat on the surface of 50 the container, but that space be allowed for the circulation of air beneath it, otherwise ignition may fail frequently. This circulation may be provided for in one of the following four ways:

First, by raising the plate from the surface by 55

the use of washers, shims, short tubes or other similar devices at the fastening screws 7-7;

Second, by a counter-sunk slot in the surface of the container, located under the bars;

5 Third, by arching the plate 5 between the fastening screws 7-7;

Fourth, by bridging the plate 5 by means of a double bend or fold near each end, between the screw holes 7A-7A and the bars of the grill so 10 that the grill is bridged above the surface of the box between the folds.

It is apparent that there are no expensive materials to be used, and nothing to get out of order. Any inflammable fluid, even ordinary gasoline, 15 can be used for moistening the match. The electric current, being used only at the moment when the match is struck, is negligible. The expense of upkeep is nil. The box can be made in any style, for setting on a table or smoking stand in 20 parlor or office, or hanging on the wall in the kitchen or work-shop; may be included as part of a lamp or other desk apparatus, or built into the instrument board of an automobile.

I claim:

25 1. In an electric lighter, the combination comprising a central member shaped to define integral electric contact means and provided with means for its connection with a source of electric energy, said grill member formed of transverse 30 integral bars having spaces between them, said grill member disposed in a position on its support to provide a space for circulation of air through and about the same, a pair of parallel plates secured respectively on each side of said 35 grill member and each plate extending upwardly and inwardly about said grill member and respectively terminating along their adjacent uppermost edges over the grill member and thus registering in a predetermined space relation sufficient to define an effective guard against unintentional contact between said grill and the same and spaced apart in their adjacent upper edges far enough only to admit of the free movement 40 of a mechanical match between said adjacent edges as it contacts said grill member; said guard 45

plates each connected to a source of electric energy and each insulated from said grill plate, said grill member adapted to be operatively connected to one pole of a battery or source of electric energy and said said guard plates each jointly connected to an opposite pole of a battery or source of electric energy, and insulation means flanking the outer surface of each of said guard plates for protection against an accidental contact therewith. 5

2. In an electric lighter, the combination comprising a central grill member shaped to define integral electric contact means and provided with means for its connection with a source of electric energy, said grill member formed of transverse 15 integral bars having spaces between them, said grill member disposed in a position on its support to provide a space for circulation of air through and about the same, a pair of parallel plates secured respectively on each side of said 20 grill member and each plate extending upwardly and inwardly about said grill member and respectively terminating along their adjacent uppermost edges over the grill member and thus registering in a predetermined space relation sufficient to define an effective guard against unintentional contact between said grill and the same and spaced apart in their adjacent upper edges far enough only to admit of the free movement 25 of a mechanical match between said adjacent edges as it contacts said grill member; said guard plates each connected to a source of electric energy and each insulated from said grill plate, said grill member adapted to be operatively connected to one pole of a battery or source of electric energy 30 and said guard plates each jointly connected to an opposite pole of a battery or source of electric energy, and insulation means flanking the outer surface of each of said guard plates for protection against an accidental contact therewith; and a resistance coil operatively connected with said guard plates in series circuit to provide protection against an inadvertent short circuit or unintentional contact with an electrical conductor. 35
